Primary Examiner — Robert Delehanty(74) *Attorney, Agent, or Firm* — Calfee, Halter & Griswold LLP(57) **CLAIM**

The ornamental design for a dispenser hub, as shown and described.

DESCRIPTION

FIG. 1 is a perspective view of a dispenser hub of the new design;

FIG. 2 is a front elevational view of the dispenser hub of FIG. 1;

FIG. 3 is a rear elevational view of the dispenser hub of FIG. 1;

FIG. 4 is a left side elevational view of the dispenser hub of FIG. 1, the right side elevational view being a mirror image thereof; and,

FIG. 5 is a top plan view of the dispenser hub of FIG. 1. The portions of the Figures shown in broken lines are not part of the claimed design and are for illustration only.
